UNITED STATES PATENT OFFICE

165,809

GUM-VENDING MACHINE

David B. Wheeler, Independence, Mo., assignor to
The Vendo Company, Kansas City, Mo., a corporation of Missouri

Application October 15, 1951, Serial No. 16,937

Term of patent 14 years

(Cl. D52—3)

To all whom it may concern:

Be it known that I, David B. Wheeler, a citizen of the United States, residing at Independence, in the county of Jackson and State of Missouri, have invented a new, original, and ornamental Design for a Gum Vending Machine, of which the following is a specification, reference being had to the accompanying drawing, forming a part thereof.

Fig. 1 is a perspective view of a gum vending machine, showing my new design; and

Fig. 2 is a side elevational view thereof.

I claim:

The ornamental design for a gum vending machine, as shown.

DAVID B. WHEELER.
